MEANS FOR FORMING AND TEMPERING
HELICAL SPRINGS

Charles A. Widgren, Flint, Mich.

Application June 23, 1938, Serial No. 215,414

6 Claims. (Cl. 140—89)

The present invention relates to means or implements for forming and tempering helical springs and the like; and its object is, generally, to provide improved means whereby such springs may be shaped into and tempered in certain finished forms, particularly forms in which the ends or end coil portions of the spring are flattened from helical into plane form, as into planes at predetermined angles to the spring's axis, and whereby the spring is held against deformation from such shaped finished form during the tempering thereof; and further, to provide improved means or implements for changing the length of such springs.

These and any other and more specific objects hereinafter appearing are attained by the illustrative preferable means or implements particularly described in the body of this specification and illustrated by the accompanying drawings, in which:

Figure 1 is an elevational side view of an implement whereby helical springs and the like may be thus formed and tempered, means for holding the spring therein being illustrated in their operative position and certain parts of the implement being shown in longitudinal vertical section;

Figure 2 is a like view thereof but showing said means in operative position and certain upper parts broken away;

Figure 3 is a top plan view of parts of the same shown partly in horizontal section taken on line 3—3 of Figure 1, one end portion only of the helical spring being shown in this view;

Figure 4 is a bottom plan view of parts thereof shown partly in horizontal section taken on line 4—4 of Figure 1;

Figure 5 is a top plan view of the same partly sectioned horizontally on the line 5—5 of Figure 2;

Figure 6 is an elevational left hand end view of parts thereof;

Figure 7 is a transverse vertical sectional view of parts of the same taken on line 7—7 of Figure 5;

Figure 8 is a transverse vertical sectional view of parts thereof taken on line 8—8 of Figure 3;

Figure 9 is a central longitudinal vertical sectional view of the same taken on line 9—9 of Figure 7;

Figure 10 is a central longitudinal vertical sectional view of the implement, illustrating a modified construction thereof;

Figure 11 is a transverse vertical sectional view thereof taken on line 11—11 of Figure 10;

Figure 12 is a transverse vertical sectional view of the same taken on line 12—12 of Figure 10.

In the manufacture of helical springs their helical shape is usually continued throughout their length or axial extent, so that their ends or end coil portions do not lie in planes, as in planes which are at a predetermined angle (as a right angle) to the spring's axis. It is therefore a main object of this invention to provide improved implements whereby such a spring may be readily and economically shaped and tempered in the finished form wherein its ends or end coil portions are positioned in such planes, so that the spring's load will be supported on its flat ends lying in such planes and whereby the springs may be lengthened or shortened in axial direction.

The helical spring 1 heated to a proper degree of pliancy is placed in the lower part 2 of an elongated container or "quenching box" 3 supported as by its leg 4 in a vessel 5 containing a cooling or quenching liquid 6, as oil, in which said container and the spring within it are immersed as indicated in Figure 2 for tempering the spring in the usual way by the rapidly cooling action of the liquid, which may be circulated through the vessel's ports 7, 8 and the container's ports 9, 10.

Means are provided for holding the spring's main portion, i. e., its coils 11 intermediate its end coil portions 12, 13, in axial alignment in the container, such means, in their illustrated form, including the longitudinally extending halves 14 of the container's bottom on whose downwardly-inwardly inclined upper surfaces the lower side of the spring seats, and which halves are spaced by the slot or port 10 through which the liquid may freely flow when the container is being drained in its position indicated in Figure 1. Such holding means includes also the lever arm 15 whose convex end 16 is turnable in a bearing 17 in the block 18 slidable in a bearing 19 in the under side of the top 20 of the container's upper part of half 21, this block being slid in the bearing 19 by a screw 22 threaded therein and journaled in said part's end 23 in order to move said arm longitudinally to adjusted positions for the purpose hereinafter explained.

It will be seen that when said upper part or half 21 of the container is slid downwardly on the guide posts 24, 25 by suitable means as by admitting fluid pressure above the head 26 of the piston 27 which carries said part, the same is forced to press this arm on the upper side of the spring, said arm's and said part's downward movement being limited by the stop 28, so that the spring's said main portion is clamped between

this arm and the container's bottom as indicated in the views. Thus said main portion of the helical spring 1 is held in axial alignment during the flattening of its end coil portions 12, 13 and the shaping or forming thereof relatively to said main portion and during the tempering of the spring.

Spaced longitudinally of the container and in the spring's axial direction, means engaging the spring's end coil portions 12, 13 respectively are provided for flattening them, for positioning the same in planes at a predetermined angle (in the shown instance, a right angle) to the axis of said main portion of the spring held in the container, and for holding said end coil portions thus flattened and formed or shaped, against deformation during the tempering thereof. Each of said means, in their illustrated form, comprises a pair of cooperating members 29, 30 or 31, 32, one of each pair as the members 29 and 31, being relatively movable in the spring's axial direction to adjusted positions to accommodate a helical spring of desired length; and the other member of each pair as the members 30 and 32, is movable relatively to the members 29 and 31.

The member 29 carried by the lever arm 15 is movable to its said adjusted position (which is fixed in the longitudinal direction of said arm and relatively to the right hand end of the container) by turning the screw 22, and the member 31 may be manually moved to its said adjusted position guidedly on the ribs 33 extending horizontally and inwardly from the sides 34 of the container's lower part or half 2 and slidably bearing in notches 35 in the opposite vertical edges of this member 31. Said member 31 is, as shown, held in its said adjusted position by turning down the screws indicated at 36 to clamp said ribs between this member's clamp blocks 37 and the under side of the notches 35; and, as shown, said member is also held in its said adjusted position by turning down the screw indicated at 38 to clamp the container's bottom's halves 14 between the lower edge of this member and the clamp block 39 which is slidable in the slot 10. It will thus be seen that this member 31 is held, at triangularly disposed points, in the position to which it has been slidably moved.

The other members 30 and 32 of the respective pairs are movable relatively to each other and relatively to the adjusted members 29, 31 of said pairs along said guiding means, the ribs 33. The members of each pair have flat adjacent faces 40, 41 or 42, 43, which in their cooperating action extend parallelly with each other and transversely of the helical spring's axis.

The member 30 of the left hand pair and the member 32 of the right hand pair are yieldingly urged apart by coiled springs 44 surrounding the horizontal rods 45 which pass freely through indicated openings 46 in member 32 and registering openings 47 in member 31, the separating movement of the members 30 and 32 being limited by stop collars 48 for member 30 and movable collars 49 for member 32, the collars 49 being held in proper adjusted slid position for a helical spring of such desired finished length by pins 50.

Means are provided for forcibly moving the members 30, 32 slidably toward the members 29, 31 of the respective pairs by the mutually approaching movement of the container's parts or halves 2 and 21, such means, in their illustrated form, including the block 51, on the left

hand end portion of the container's upper part or half, for moving the member 30, and the block 52, adjustable to position in the right hand end portion of said upper half, for moving the member 32, this block 52 being manually movable to adjusted position corresponding to the position of member 32 whose stop collar 49 has been adjusted to the proper position for accommodating a helical spring of the desired length.

This block 52 is secured in its adjusted position by suitable means which, in their illustrated form, include screws 53 extending through elongated openings or slots 54 in the top 20 of the container's upper part or half 21, and screws 55 extending through such openings or slots 56 in said part's opposite sides 34, these screws having heads and being threaded in this block and turnable for clamping said block in its adjusted position.

The block 51 and its cooperating member 30, 20 and the block 52 and its cooperating member 32 have mutually adjacent relatively inclined side portions which slide on each other in the downward movement of said upper part 20 for wedgingly forcing the members 30 and 32 toward the members 29 and 31 respectively. Such inclined portions 58, 59 of block 51; 60, 61 of member 30; 62, 63 of block 52 and 64, 65 of member 32, are spaced in the direction of said blocks' vertical movement so that the mutually adjacent faces of the members of each of the pairs are always maintained in parallel relation.

The inner side 66 of member 29 is inclined relatively to its outer side or face 40 so that this member may more readily enter between the end coil portion 12 and the next coil 11 in the downward movement of the container's upper part or half. A helical groove as indicated at 67 in Figure 8 may be formed in the face 42 of member 31 for receiving the free end part of the end coil portion 13 of the spring so that one end coil portion of the spring will not be completely flattened, in cases where this may seem desirable.

A headed rod 68 extending through the container's top and threaded in the lever arm 15, with a cushioning spring 69, may be provided for preventing this arm from falling too far when said upper half is raised.

In the modified construction of the implement 50 as illustrated by Figure 10, a member extending in the container's longitudinal direction and engaging one side of the helical spring therein, as the lever arm 15 in the container's closed position, may be provided with spaced inward extensions or lugs 70 engaging between the coils 11 of the main portion of the spring for holding said coils in properly spaced relation and holding said main portion axially relatively to the end coil portions 12, 13. These extensions or lugs have inclined sides 71 for moving these coils into such spaced relation.

This implement is operated, in the following manner:

For adapting the implement to accommodate a helical spring of desired finished length, the lever arm 15 is by turning the screw 22 slid for moving the member 29 to proper adjusted position and the block 52 is slid to proper adjusted position and held therein by turning down the screws 53, 55. The member 32 is slid to proper position for cooperating with the block 52 and is held against the pressure of the coiled springs 44 by adjusting the collars 49 in their proper fixed position, and the member 31 is slid to and held in 75

proper adjusted position for cooperating with the member 32. The helical spring, heated to the proper degree of pliancy and for tempering, is placed in the lower part or half 2 of the container 5 with the transaxial outer side of its left hand end coil portion 12 at or adjacent to the face 41 of the member 30 and its right hand end coil portion 13 positioned between the cooperating members 31, 32 of the right hand pair.

10 Power being applied, as to the piston 27, the container's upper part or half is forced downwardly from its raised position. In this movement wedge shaped member 29 enters between the spring's left hand end coil portion 12 and the next coil 11 of its main portion and as said movement continues this member 29, frictionally engaging the inner transaxial side of said end coil portion or the adjacent transaxial side of said coil 11, causes arm 15 to turn upwardly until 15 stopped by the bottom of the groove 19, thus causing the face 40 of this member 29 to assume a position parallel with the face 41 of member 30. The members 30, 32 of the respective pairs are by said downward movement of said upper 20 half now forced toward their cooperating members 29, 31 respectively thus flattening the spring's end coil portions 12, 13 between the members of said pairs respectively into planes at the predetermined angle (in the illustrated instance, a right angle) to the axis of the spring's main portion. This same action also forms the spring into the desired finished length.

To this end the parts cooperate in the following manner: Member 29 of the left hand pair carried 35 by or connected to the upper side or half 21 of the quenching box and member 31 of the right hand pair carried by or connected with the box's lower side or half 2, may be moved in the spring's axial direction and secured in desired adjusted positions on said sides respectively. These members 29, 31 thus form abutments or stops for defining the length of the finished spring. The spring is laid in the box's lower half with the inner side of its end coil 13 adjacent the right 40 hand side 42 of member 31; the box's upper half being now forced down, the member 29 of the left hand pair entering between coils 11, 12 determines the position of the left hand end coil 12 and engaging this end coil moves it to the left 45 to lengthen the spring or engaging the adjacent coil 11 moves it toward the right to shorten the spring, and this downward movement of said upper half also causes, by means of the blocks 51, 52, the members 30, 32 of said pairs to move toward the members 29, 31 for clamping and flattening said end coil portions or convolutions.

It will be seen that the lever arm 15 in the lowest position of the container's upper part 21 engages the upper side of the spring's main portion, i. e. the coils 11, thus holding said portion in axial alignment, and that in the modified construction shown in Figure 10 the inclined sides 71 of the spaced inward extensions or lugs 70 engaging said coils 11 move the same into properly spaced relation. The helical spring thus shaped or formed and while held in such shape or form is tempered by subjecting the same to the rapidly cooling action of the liquid.

The spring is thus formed or shaped by bending the same and its portions relatively to each other while heated to a sufficiently pliant degree, and is tempered into finished form and shape while thus held.

The forming of the end coil portions of the spring in planes at predetermined angles to the

axis of its main portion is thus effected by positioning the adjacent faces of the members of these pairs at the same angle to the longitudinal direction of the means 14, 15 whereby said main portion is held in the container.

It will thus be seen that the pliantly heated spring may be lengthened or shortened by properly adjusting the position of the pairs of said members and operating the implement thus adjusted.

The invention being intended to be pointed out in the claims, is not to be limited to or by details of the method, or details of construction and arrangement of the particular implement illustrated or hereinbefore shown or described.

I claim:

1. An implement of the class described for shaping pliantly-heated helical springs and the like held therein to a predetermined set form, said implement including: means at the opposite 20 sides of the implement comprising cooperating members having a mutually approaching movement into engagement with the adjacent sides of the spring for holding the same against transaxial movement, means at one end of the implement 25 engaging one end convolution of the spring for holding said convolution against movement in the spring's axial direction; and means at the other end of the implement comprising a pair of cooperating members relatively movable into 30 clamping engagement with the opposite sides of the other end convolution of the spring for flattening said convolution and bending the same 35 clamped therebetween into a predetermined plane transaxial of the spring.

2. An implement of the class described for shaping pliantly-heated helical springs and the like held therein to a predetermined set form, said implement including: means at the side of the implement having a movement toward the 40 adjacent side of the spring and having spaced transverse recesses adapted to receive coils respectively of the spring for holding the same against relative movement in the spring's axial direction; and means at one end of the implement 45 comprising a pair of cooperating members relatively movable into clamping engagement with the opposite sides of an end convolution of the spring for flattening said convolution and bending the same clamped therebetween into a 50 predetermined plane transaxial of the spring.

3. An implement of the class described for shaping pliantly-heated helical springs and the like held herein to a predetermined set form, said implement including: a pair of cooperating 55 members at each end of the implement the members of each pair being relatively movable into clamping engagement with the adjacent end convolution of the spring for flattening and bending the same into a predetermined plane 60 transaxial of the spring, one member of at least one of said pairs being movable relatively to the other pair parallelly with the spring's axis to an adjustably fixed position for defining the length 65 of the finished spring.

4. An implement of the class described for shaping pliantly-heated helical springs and the like held therein to a predetermined set form, said implement including: a pair of cooperating members at each end of the implement the 70 members of each pair being relatively movable into clamping engagement with the adjacent end convolution of the spring for flattening and bending the same into a predetermined plane 75 transaxial of the spring, one member of at least

one of said pairs being movable relatively to the other pair parallelly with the spring's axis to an adjustably fixed position for defining the length of the finished spring; and means for moving the members of said pairs into their said engagement with the spring's end convolutions respectively.

5. An implement of the class described for shaping pliantly-heated helical springs and the like to a predetermined set form, said implement including: a box having opposite sides connected for mutually approaching lateral movement to a 5 position wherein the spring is held therebetween against transaxial movement; a pair of cooperating members in the box at each end thereof the members of each pair being relatively movable into clamping engagement with the adjacent end convolution of the spring for flattening and bending the same into a predetermined plane transaxial of the spring, one member of at least one pair being connected with one side of the box the other member of the same pair 15 being connected with the other side of the box and one member of said pair being movable parallelly with the spring's axis to an adjustably fixed position for defining the length of the spring, the adjustably fixed member being adapted to engage by the approaching movement of said sides the adjacent end convolution of the spring for lengthening or shortening the spring to the limit defined by said adjustably fixed member's fixed position.

6. An implement of the class described for shaping pliantly-heated helical springs and the like to a predetermined set form, said implement including: a box having opposite sides connected for mutually approaching lateral movement to a 5 position wherein the spring is held therebetween against transaxial movement; a pair of cooperating members in the box at each end thereof the members of each pair being relatively movable into clamping engagement with the adjacent end convolution of the spring for flattening and bending the same into a predetermined plane transaxial of the spring, one member of at least one pair being connected with one side of the box the other member of the same pair 15 being connected with the other side of the box and one member of said pair being movable parallelly with the spring's axis to an adjustably fixed position for defining the length of the spring, the adjustably fixed member being 20 adapted to engage by the approaching movement of said sides of the adjacent end convolution of the spring for lengthening or shortening the spring to the limit defined by said adjustably fixed member's fixed position; and a block mounted on one side of the box at each end thereof having an inclined side slidably engaging the movable member of a pair on the other side of the box for moving the same toward the cooperating fixed member of said pair by the 25 approaching movement of said sides.

CHARLES A. WIDGREN.
